UNITED STATES PATENT OFFICE

2,605,483

BED SHEET

Joseph C. Ridenhour, Kannapolis, N. C., assignor
to Cannon Mills Company, Kannapolis, N. C.,
a corporation of North Carolina

Application August 1, 1949, Serial No. 107,940

5 Claims. (Cl. 5—335)

1

This invention relates to bed clothing and more especially to bed sheets of a type sometimes referred to as crib sheets. It is an object of this invention to provide a bed sheet so formed that it can be fitted onto a mattress in such a manner that it cannot be accidentally dislodged from the mattress, either at the ends thereof or at the sides, and this is accomplished by turning down the sides and ends and securing the same together to provide a bed sheet having side portions and end portions covering the sides and ends of the mattress and also extending underneath the sides and ends of the mattress and covering the marginal portions of the bottom surface of the mattress to thereby make it practically impossible for the sheet to become dislodged from the mattress due to restlessness of the sleeper. It also provides a smooth surface at all times for the sheet in that it is stretched over the mattress and confined against lateral or longitudinal movement relative to the mattress.

It is another object of this invention to provide a bed sheet formed from a single sheet of cloth by cutting away the four corner portions of the blank along straight lines diverging from each other and gradually increasing the angularity of the straight lines as they progress from the apex of the corner portion outwardly to the marginal portions of the sheet thus forming end panels and side panels, and then seaming the ends of the side panels of the sheet to the ends of the end panels of the sheet along the angularly disposed straight lines to thus provide a sheet which can be easily installed upon a mattress and which is not susceptible to accidental removal as to any portion thereof. This results in no waste of material.

Some of the objects of the invention having been stated, other objects will appear as the description proceeds, when taken in connection with the accompanying drawings, in which

Figure 1 is a plan view of the blank cut and ready for a sewing operation;

Figure 2 is an isometric view showing one end of one of the side panels and one end of one of the end panels sewed together with a suitable binding strip and showing the corner portion turned inside out;

Figure 3 is a view similar to Figure 2 but showing the binding strip along the edges of the end and side panels in addition to the binding strip at the junction point of the end and side panels;

Figure 4 is an enlarged isometric view looking down on the inside of one corner of the bed sheet and showing the inner or wrong side of the same;

2

Figure 5 is an isometric view looking at the bottom of the bed sheet in the form it would appear as when installed on a mattress.

Referring more specifically to the drawings, the numeral 10 indicates a sheet of cloth from which a bed sheet or crib sheet is to be made, and this sheet of cloth is cut away at its four corners as illustrated such as by cutting a straight line 11 and then another straight line 12 forming an obtuse angle on the lower side of the lines 11 and 12 at their junction point, and then cutting along the line 13 forming another obtuse angle on the lower side at the junction points of lines 12 and 13, and then cutting another straight line 14 joined to the line 13 by another obtuse angle on its lower side. The line 15 is then cut similar to line 11, then line 16 is cut, which is similar to line 12, and then the blank is cut along the line 17 which is identical to line 13, and finally the blank is cut along the line 18 to join the inner end of line 14. Since all four corners are identical, like reference characters will apply to the four corners.

After the corner portions are cut away, it provides side panels 30 and 31 to cover the sides of the mattress and end panels 32 and 33 which cover the two ends of the mattress.

With the blank cut in the form shown in Figure 1, the lines 14, 13, 12 and 11 are seamed to the edges 18, 17, 16 and 15, respectively, by a line of stitches 20 and in order to take up as little fabric as possible and yet provide a strong junction between the side and end panels, a binding strip 21 is sewed over these proximate edges by the line of stitches 20 which also penetrates the proximate edges of the side and end panels. This binding strip 21 is so disposed as to be on the wrong side of the fabric or the inside of the finished bed sheet. After the four corners have been thus sewed together, the edges of the side and end panels have applied thereto a binding strip 22 by a line of stitches 23 which also passes over the binding strip 21 for the corner structure, and thus the bed sheet is completed.

All that appears at the four corners is a junction line indicated at 26, as the binding strip 21 is disposed on the inside of the completed bed or crib sheet.

It might be added by explanation that, instead of cutting two straight lines of the proper angularity for the corner structures, each corner structure represents four straight lines disposed at an obtuse angle with relation to each other and gradually diverging away from each other as they progress from the apex indicated at A to the outer edges of the end and side panels, which is done

for the reason that a mattress does not have square corners like a box, but the upper and lower edges of the corners are rounded and thus it is necessary to cut the corner portions as indicated by a series of straight lines gradually diverging away from each other as they progress from the apex or their junction point outwardly to the outer edges of the blank so that when seamed together, they will provide a proper form fitting pocket at the junction of lines 14 and 18 and also at the junction of the lines 11 and 15.

In the drawings and specification there has been set forth a preferred embodiment of the invention, and although specific terms are employed, they are used in a generic and descriptive sense only, and not for purposes of limitation, the scope of the invention being defined in the claims.

I claim:

1. A blank for a bed sheet formed from a rectangular blank of cloth and having each of its four corner portions cut away along two series of short intersecting lines diverging in step by step relation to each other as they proceed from a single point of origin to the side and end edges of the blank, the first of the diverging lines forming an acute angle at their junction point and the succeeding lines of each series at their junction point forming a plurality of obtuse angles, the edges on the end and side portions of the blank being adapted to be joined together by a continuous seam.

2. A blank for a bed sheet formed from a rectangular blank of cloth having each of its four corner portions cut away thus forming end panels and side panels adapted to cover the ends and sides of a mattress, the end panels and side panels being adapted to be joined together by a continuous seam, each of the end panels and side panels being defined by a plurality of short intersecting straight lines, the first or innermost lines defining the ends of the end and side panels forming an acute angle at their common point of origin and the remaining lines defining the ends of the panels forming a plurality of obtuse angles and the plurality of short intersecting lines on the adjacent ends of a pair of panels successively diverging from each other.

3. A blank for a bed sheet comprising a substantially rectangular body portion adapted to cover the upper surface of a mattress, said sheet being provided with a pair of opposite side panels, and a pair of opposite end panels, said side and end panels both extending outwardly from said body portion substantially the same distance, adjacent edges of said end and side panels being defined by two diverging lines of cut, each of said lines of cut comprising four straight segments, the first segments of the diverging lines of cut forming an angle of approximately 45 degrees with relation to each other, and the second seg-

ments of the diverging lines of cut forming an angle with relation to each other of slightly more than 90 degrees, the third segments of the diverging lines of cut forming an angle with relation to each other of greater than 120 and less than 180 degrees, and the fourth segments of the diverging lines of cut forming an angle with relation to each other on their outer surfaces of greater than 180 degrees.

- 5 10. 4. A cover for enveloping one face and the opposite sides and ends of a mattress, the cover being formed from a rectangular blank of cloth and including a central panel and side and end panels, the side and end panels being connected together at the four corners of the cover by seams located one at each of the corners and which join the opposite edges of an indentation which has been formed at such corner of the rectangular blank, the indentation at each corner being 15 formed by cutting away the material to provide a pair of similar outlines diverging from an acute angle at the inner end of the indentation and arranged symmetrically on opposite sides of the axis bisecting the angle of such indentation and 20 providing pairs of short diverging lines, the lines of each pair being arranged on opposite sides of the axis and the divergence of the lines of the respective pairs increases progressively from such angle to the end of the indentation.
- 25 30. 5. A cover for enveloping one surface and the opposite sides and ends of a mattress, the cover being formed from a rectangular blank of cloth and including a central panel and side and end panels, the vertical height of the side and end panels being greater than the vertical height 35 of the mattress, the side and end panels being connected together at the four corners of the cover by seams located one at each of the corners and which join the opposite edges of an indentation 40 which has been formed at such corner of the rectangular blank, the indentation at each corner being formed by cutting away the material to provide a pair of similar outlines diverging from an acute angle at the inner end of the indentation and arranged symmetrically on opposite sides of the axis bisecting the angle of such indentation, the outlines gradually diverging from each other, and the divergence of the outlines of the respective pairs increasing progressively from such 45 angle to the end of the indentation.
- 50 55. 6. A cover for enveloping one surface and the opposite sides and ends of a mattress, the cover being formed from a rectangular blank of cloth and including a central panel and side and end panels, the vertical height of the side and end panels being greater than the vertical height of the mattress, the side and end panels being connected together at the four corners of the cover by seams located one at each of the corners and which join the opposite edges of an indentation which has been formed at such corner of the rectangular blank, the indentation at each corner being formed by cutting away the material to provide a pair of similar outlines diverging from an acute angle at the inner end of the indentation and arranged symmetrically on opposite sides of the axis bisecting the angle of such indentation, the outlines gradually diverging from each other, and the divergence of the outlines of the respective pairs increasing progressively from such angle to the end of the indentation.
